(57) **CLAIM**

The ornamental design for a bedstead, as shown and described.

DESCRIPTION

FIG. 1 is a left front perspective view of a bedstead showing my new design;

FIG. 2 is a side elevational view, the opposite side being a mirror image thereof;

FIG. 3 is a front elevational view of the headboard section thereof;

FIG. 4 is a front elevational view of the footboard section thereof; and,

FIG. 5 is a rear perspective view of the footboard section thereof.

The bottom view of the bedstead and the rear view of the headboard section are not shown and form no part of the claimed design. The dashed lines represent environmental elements only and form no part of the claimed design.
